W. H. ETTER.
WINDOW SCREEN.
APPLICATION FILED MAY 9, 1910.

Patented May 14, 1912.

UNITED STATES PATENT OFFICE

WILLIAM H. ETTER, OF MARIETTA, OHIO.

WINDOW-SCREEN.

1,026,501.

Specification of Letters Patent. Patented May 14, 1912.

Application filed May 9, 1910. Serial No. 560,309.

To all whom it may concern:

Be it known that I, WILLIAM H. ETTER, a citizen of the United States, residing at Marietta, in the county of Washington and 5 State of Ohio, have invented a new and useful Window-Screen, of which the following is a specification.

The invention relates to improvements in window screens.

10 The object of the present invention is to improve the construction of window screens, and to provide a simple, practical and efficient metallic window screen of comparatively inexpensive construction, designed to 15 be hung exteriorly of the sashes and adapted to be swung inwardly and outwardly, and equipped with means adapted to support the screen upon the window sill even when the screen frame is located beyond the 20 same, whereby the window screen will be firmly maintained in its closed position and may be locked to the sill.

A further object of the invention is to produce a metallic window screen, provided 25 with resilient means for supporting each of the marginal portions of the wire netting and of permitting a uniform expansion and contraction of the same without twisting the frame of the screen or buckling the wire.

30 Another object of the invention is to provide a window screen, equipped with lateral extensions removable to permit extensions of different widths to be employed, and adapted to be readily cut or trimmed to fit a 35 window frame, and capable of enabling window screens of a given height to be applied to windows varying in width up to six or eight inches, whereby the number of sizes necessary to carry in stock will be materially reduced.

With these and other objects in view, the invention consists in the construction and novel combination of parts hereinafter fully described, illustrated in the accompanying 45 drawing, and pointed out in the claims hereto appended; it being understood that various changes in the form, proportion, size and minor details of construction, within the scope of the claims, may be resorted 50 to without departing from the spirit or sacrificing any of the advantages of the invention.

In the drawing:—Figure 1 is a perspective view of a window screen, constructed 55 in accordance with this invention and shown applied to a portion of a window, one side

of the latter being sectioned. Fig. 2 is an enlarged vertical sectional view of the same. Fig. 3 is a horizontal sectional view of one side of the window screen and the window frame. Fig. 4 is a similar view, illustrating another form of the extension strip. Fig. 5 is a detail perspective view, illustrating the construction of one of the corners of the screen frame.

Like numerals of reference designate corresponding parts in all the figures of the drawing.

In the accompanying drawing in which is illustrated the preferred embodiment of the invention, the improvements are shown applied to a window screen, but the construction of the screen frame and the manner of mounting the wire netting 1 may be applied to screen doors with equal advantage. The screen frame, which is constructed of sheet metal, consists of two rectangular clamping sections 2 and 3, composed of channel bars rigidly secured together at their ends by the means hereinafter described. The wire netting is clamped between the inner and outer rectangular clamping sections 2 and 3, and the outer vertical side channel bars of the clamping section 2 are provided at each end with a horizontally disposed lateral extension 4, which is fitted against the outer faces of the contiguous horizontal channel bars, as clearly shown in Fig. 5, and the horizontal bar is provided with a vertical extension 5, fitted 80 against the inner face of the vertical side channel bar.

The extensions 4 and 5 are riveted or otherwise secured to the channel bars against which they are fitted. The vertical 95 channel bars are also provided at their ends with integral horizontal lugs 6 and 7, bent inwardly at right angles and fitted against the outer upper and lower faces of the horizontal channel bars, and soldered or otherwise secured to the same. The top lugs 6 are also pierced by the shanks 8 of hooks 9 with which the screens are designed to be equipped to enable them to be hung from pins, or other suitable fastening devices. 100 The shanks 8 of the hooks 9 also pierce the top flange 10 of the top horizontal channel bar of the rectangular clamping section 2, and are bent against the inner face of the said flange 10 and form additional fastening 110 means. The inner rectangular clamping section 3 of the screen frame is composed of

vertical and horizontal channel bars, provided at their ends with horizontal and vertical extensions 11 and 12, which overlap the contiguous channel bars and are riveted, or otherwise secured to the same. The horizontal lateral extensions 11 are formed integral with the vertical channel bars, and are located at the ends thereof, and the vertical extensions project from the terminals 10 of the horizontal channel bar of the said inner rectangular clamping section 3. The corner joints of both the inner and outer rectangular clamping sections are reinforced, and the channel bars are securely 15 connected without producing exterior side projections, which would space the screen from the sides of a window frame and form openings through which insects might pass.

The inner rectangular clamping section 20 3 is fitted snugly within the outer rectangular clamping section 2, and is arranged between and contiguous to the inner and outer side flanges thereof, and it engages each of the marginal edges or portions 13 25 of the wire netting 1, which is angularly bent, as clearly shown in Fig. 4, whereby it is securely clamped and fastened to the screen frame.

The inner flanges 14 of the outer rectangular clamping section 2 are resilient, and their ends 15 are not connected with the adjacent parts, and are free to move both inwardly and outwardly to enable the said inner flanges 14 to spring inward and outward uniformly throughout their entire length, and thereby permit the wire netting to expand and contract without buckling and twisting the metallic frame. The flange 14, which engages the outer face of 40 the screen, terminates short of and adjacent to the plane of the center of the frame of the screen, so that the wire netting will occupy a central position within the frame mid-way between the inner and outer faces 45 of the same. The inner and outer faces of the screen frame are formed by the channel bars, which present flat exterior faces extending from the inner to the outer flanges of the channel bars. This operates to produce a uniform strain on all portions of the frame.

The inner and outer rectangular clamping sections 2 and 3 are secured together at intervals by screws 16, or other suitable 55 fastening devices, which pierce the outer side flanges of the channel bars, and are embedded in wooden blocks 17, arranged at suitable intervals, four being ample for each side of a window screen. The blocks are located between the side flanges of the channel bars and are concealed within the screen frame.

The window screen may be hung by hooks 9 between the stop or guide strips 18 of a 65 window frame, but in order to enable the

window screen to be fitted to windows of different widths, it is equipped at opposite sides with laterally extending vertically disposed strips 19, each having an attaching member 20, arranged at right angles to the vertical strip and secured to the screen by the fastening devices 16.

In Figs. 1 to 3 inclusive, the attaching member of the laterally extending strip is approximately U-shaped, and is fitted over the outer side flange of the outer rectangular clamping section 2. This arranges the vertical strip 19 in flush relation with the outer face of the frame of the screen, and enables the window screen to be located between the stop strips 18.

In Fig. 4 of the drawings is illustrated a laterally extending strip 21, provided with a straight flange 22, fitted between the outer flanges of the inner and outer rectangular clamping sections, and secured by the fastening devices thereof. This arranges the strips 21 in flush relation with the inner face of the frame of the window screen, which is thereby caused to project outward beyond the stop strips. Either form of the laterally extending strips may be employed, and the strips may be varied in width to enable them to overlap the stop strips of a window frame to the desired extent. The vertical strips are provided at their upper ends with extensions 23, having perforations 24 adapted to be hung on hooks 25, or other suitable fastening means. The shanks of the hooks are embedded in the outer faces 100 of the stop strips 18, and the screen is adapted to swing outwardly and inwardly, and it is provided at the bottom with a flange 26, preferably consisting of an extension of the bottom flange of the outer 105 rectangular clamping section, and adapted to rest upon the sill 27 of the window frame. The flange 26, which is arranged at right angles to the window frame, is adapted to clear the upper face of the sill 27, which 110 inclines downwardly and outwardly. When the screen is equipped with the strips 21 and is located beyond the sill, as illustrated in Fig. 4 of the drawing, the flange 26 serves as a supporting base and relieves the 115 hooks of strain and enables the bottom of the screen to be fastened to the window sill. The top flange 10 operates as a meeting strip or flange and extends to the bottom of the upper sash, so as to close the space 120 between the same and the screen. When the screen is hung at the top of the window, the bottom flange is adapted to be used as a meeting strip and fitted against the top of the upper sash when the latter is open. The 125 sill is preferably equipped with a resilient catch 28, mounted in a recess 29 and adapted to engage an opening 30 of the flange 26. The catch is preferably rounded at its engaging portion, so that the window screen 130

5 may be automatically engaged with and disengaged from the catch, when the necessary force is applied. The screen is provided with a grip or handle 31, preferably consisting of a loop and adapted to enable the screen to be readily swung outwardly or inwardly and engaged with and disengaged from the catch.

10 Having thus fully described my invention, what I claim as new and desire to secure by Letters Patent, is:—

15 1. A screen of the class described including a frame comprising two approximately rectangular clamping sections removably fitted together and each composed of channel bars rigidly secured together at their ends, wire netting having its marginal portion clamped between the inner sides or flanges of the channel bars, the inner sides or flanges of the outer frame member having their terminals free to permit such inner flanges to spring inward and outward uniformly to enable the netting to contract and expand without twisting the frame or buckling the wire, and fastening devices piercing 20 the outer sides or flanges of the channel bars and detachably connecting the two clamping sections together.

25 2. A screen of the class described including a frame comprising inner and outer rectangular clamping sections detachably fitted together and each composed of channel bars provided at the corners of the clamping sections with overlapping angularly disposed extensions, the outer clamping section being also provided at the top and bottom with inwardly extending lugs, said extensions and lugs being secured to the contiguous channel bars and rigidly 30 connecting the same at the corners of the clamping sections, and wire netting having its marginal portion clamped between the interfitting clamping sections.

35 3. A screen of the class described including a screen frame comprising two rectangular clamping sections detachably fitted together and each composed of channel bars rigidly secured together at their ends, fastening means for detachably securing the clamping sections together, and detachable vertical strips extending from the top to the bottom of the screen and secured to the same by the said fastening means for the clamping sections forming lateral extensions of the screen and provided with attaching means secured between the outer flanges of the channel bars of the clamping sections.

40 4. A screen of the class described including a screen frame comprising two rectangular clamping sections detachably fitted together and each composed of channel bars connected together at their ends, wire netting having its marginal portions held 45 between the inner flanges of the channel

bars, and detachable angle strips extending from the top to the bottom of the screen and forming lateral extensions, which project over the face of the window casing, said angle strips also forming inner attaching 70 members fitted between the outer flanges of the clamping sections, and fastening devices piercing the said outer flanges and the attaching members of the angle strips and securing the latter and the clamping sections 75 together.

5. A screen of the class described including a screen frame comprising two rectangular clamping sections detachably fitted together and each composed of channel bars 80 connected together at their ends, fastening means for detachably securing the clamping sections together, wire netting having its marginal portion held between the inner flanges of the channel bars, and detachable 85 vertical strips extending from the top to the bottom of the screen and forming lateral extensions of the screen and provided with approximately U-shaped attaching members fitted around the outer flanges of the channel bars of one of the clamping sections and secured between the same by the said fastening 90 means for the clamping sections and the outer flanges of the channel bars of the other clamping section.

95 6. A screen of the class described including wire netting, and a screen frame comprising two rectangular clamping sections detachably fitted together and each composed of channel bars connected together at 100 their ends, the netting being clamped between the inner flanges of the channel bars, and the outer flanges of the top and bottom channel bars of the outer clamping section being extended inwardly beyond the plane 105 of the frame of the screen to form projecting meeting and supporting flanges, the meeting flange of the top channel bar being arranged to fit against the upper sash and the supporting flange of the bottom channel 110 bar being provided with an opening, and a catch designed to be mounted on a window sill and provided with means for engaging the opening of the said supporting flange.

115 7. A screen of the class described including a screen frame comprising two rectangular clamping sections detachably fitted together and each composed of channel bars connected together at their ends, fastening means for securing the clamping sections 120 together, wire netting clamped between the inner flanges of the channel bars, detachable vertical strips extending from the top to the bottom of the screen and secured between the outer flanges of the channel bars by the 125 said fastening devices and forming lateral extensions of the screen, and means for hinging the upper ends of the vertical strips to a window frame.

130 8. A screen of the class described includ-

- ing wire netting, a screen frame comprising two rectangular clamping sections detachably fitted together and each composed of channel bars connected together at their 5 ends, the netting being clamped between the inner flanges of the channel bars, and the outer flanges of the bottom channel bar of the outer clamping section being extended inwardly beyond the plane of the frame of 10 the screen to form a projecting supporting flange, said supporting flange being provided with an opening, and a resilient catch

designed to be mounted on a window sill and arranged to automatically engage the opening in the supporting flange when the 15 screen is forced to its closed position.

In testimony, that I claim the foregoing as my own, I have hereto affixed my signature in the presence of two witnesses.
